MACHINE FOR APPLYING DECALCOMANIAS

William M. Muir, South Orange, N. J.

Application July 15, 1941, Serial No. 402,548

21 Claims. (Cl. 41—1)

This invention relates to a machine for applying decalcomanias to articles.

Decalcomanias are being used commercially in increasing quantities for a variety of purposes such as tax stamps on cigar, cigarette and other packages as well as on bottles and cans; as trademarks on eggs; and as designs on knife handles and various other articles of manufacture.

The decalcomanias in their various uses are now applied by hand which is, at best, a slow and expensive process. It is, therefore, the main object of this invention to provide an entirely automatic machine for applying decalcomanias to any articles for which they are intended.

Another object of the invention is to provide a machine of this character which will automatically feed decalcomanias from a magazine and apply them to the articles.

A further object of the invention is to provide a machine for applying a predetermined number of decalcomanias at the same time.

A still further object of the invention is to provide an automatic machine that is relatively simple in construction and operation.

Other objects of the invention will become apparent from the following description of the embodiment of the invention shown in the accompanying drawings.

The embodiment of the invention shown in the drawings is a machine for applying decalcomanias in the form of tax stamps to cigarette packages. A modified form of the invention is also shown in the drawings which illustrates a machine for applying decalcomanias to eggs as trade-marks.

Although I have shown machines for applying decalcomanias to cigarette packages and eggs as illustrative embodiments of the invention, it is contemplated that the invention may be incorporated in machines for applying decalcomanias to any articles that may be desired.

In the accompanying drawings, wherein like numerals designate like parts:

Figure 1 is a front elevation of a machine embodying the invention with certain parts broken away;

Figure 2 is a side elevation of the machine as seen from the right hand side of Figure 1;

Figure 3 is a top plan view of the machine;

Figure 4 is an enlarged side view of the main drive shaft of the machine and the indexing turret on which decalcomanias are placed;

Figure 5 is a section view taken on the line 5—5 of Figure 4;

Figure 6 is an enlarged fragmentary horizontal

sectional view showing the mechanism for feeding decalcomanias from a supply to the turret;

Figure 7 is a fragmentary vertical sectional view with parts broken away showing the feeding mechanism;

Figure 8 is a sectional view showing parts of the operating mechanism for the feeding mechanism;

Figure 9 is an enlarged plan view of the pick-up slide and mechanism shown in retracted position;

Figure 10 is a similar view showing the slide in projected position;

Figure 11 is an enlarged vertical sectional view taken on the line 11—11 of Figure 3 showing the supporting structure for the pick-up slide;

Figure 12 is a side elevation of a pick-up shoe;

Figure 13 is a bottom view thereof;

Figure 14 is an enlarged fragmentary plan view showing the mechanism for removing used strips from the turret;

Figure 15 is a diagrammatic view showing the fluid system and cams for operating the valves in the system;

Figure 16 is a plan view of a modified form of pick-up slide and mechanism;

Figure 17 is a vertical sectional view showing the pick-ups used in this modification and the holders therefor;

Figure 18 is a horizontal sectional view of the pick-ups taken on the line 18—18 of Figure 17;

Figure 19 is a rear view of a modified turret wheel; and

Figure 20 is a sectional view thereof taken on the line 19—19 of Figure 18.

The application of decalcomanias in the form of tax stamps to packages of cigarettes has heretofore been accomplished commercially by removing one side of a carton to expose one end of each of the cigarette packages in the carton. The decalcomanias are then applied to each of the packages by hand. According to the present invention, the machine shown in the drawings is designed to apply decalcomanias automatically to the exposed ends of the cigarette packages after one side of the carton has been opened.

Manufacturers of decalcomanias usually supply them in large sheets which may be cut into smaller sheets or strips of desired shape containing any number of decalcomanias. The decalcomanias are usually attached to the sheets by an adhesive which will dissolve in water to permit removal of the decalcomanias. For use in the machine shown in Figures 1—15 of the drawings, these sheets are preferably cut into

strips containing ten decalcomanias arranged in a single row.

As shown particularly in Figure 1, a supply of these strips is placed in a magazine 1 on the machine from which individual strips are removed by a feeding mechanism 2 and transferred to one of the faces of a turret wheel 3. The decalcomanias on the turret wheel are indexed through a moistening medium in the form of a container 4 of water or other suitable liquid to dissolve the adhesive, and then to a position in front of a transfer mechanism 5 which removes the moistened decalcomanias from the strip and applies them to each of ten packages of cigarettes 6A in a carton 6. The strip remaining on the turret is removed after another indexing step by a rake 7.

The machine has a suitable framework conveniently formed of angle iron and consisting of four vertical supports 8, 9, 10 and 11, arranged at the corners of the machine. The supports 9 and 10 are connected by three horizontal members 12, 13 and 14 on one side of the machine, and supports 8 and 11 are connected by horizontal members 15, 16 and 17 on the opposite side of the machine. The sides of the framework are connected by horizontal members 18, 19 and 20 in front and by horizontal members 21, 22 and 23 in the rear of the machine.

The power for driving the various parts of the machine is furnished by an electric motor 24 mounted on a plate 25 that is supported by the horizontal member 21 and a similar member 26 extending between the sides of the framework. As may best be seen in Figure 3, a shaft 27 is supported by bearings 28 and 29 which are mounted on horizontal members 21 and 26, respectively. A pulley 30 is mounted on one end of the shaft 27 and is connected by a belt 31 to another pulley 32 that is driven by the motor 24 through a reduction gear enclosed in a housing 33. A gear 34 on the shaft 27 meshes with a gear 35 to drive a shaft 36 that is the main shaft of the machine. The main shaft 36 is supported by bearings 37 and 38 mounted on horizontal members 39 and 40, respectively, that extend between members 13 and 16.

As will hereinafter more fully appear, all of the mechanically operated mechanisms which make up the machine are actuated by the main shaft 36 and each revolution of this main shaft effects one operation of each of the mechanisms.

A cam 41 is mounted on the end of the main shaft (Figures 4 and 5) and has a stud 42 on one face that is arranged to engage slots 43 in a Geneva wheel 44. The Geneva wheel 44 and also the turret wheel 3 are mounted on a shaft 45 that is supported by bearings 46 and 47 which are mounted on horizontal member 19 and a similar member 48. The turret 3 as shown in the drawings, has eight faces 49, but it is contemplated that any desired number of faces may be used without departing from the scope of the invention. The Geneva wheel 44 has eight slots 43 corresponding to the faces on the turret 3, so each revolution of shaft 36 causes one-eighth of a revolution, or one indexing movement of the Geneva wheel 44 and turret 3. For convenience in the description of the machine, the eight positions of the faces of the turret have been designated A, B, C, D, E, F, G and H as shown in Figure 1, and will be hereinafter referred to by these letters.

As shown in Figure 5, the cam 41 moves a follower 50 on one end of a bell crank lever 51 that

is pivotally supported by a pin 52. The other arm of the lever 51 carries a locking pin 54 which is moved into engagement with one of a series of notches 55 in the Geneva wheel when the follower 50 is moved upwardly by the cam 41. The cam is arranged so the pin 54 is withdrawn from the notch 55 by a spring 56 just before the stud 42 engages a slot 43 in the Geneva wheel, and is moved into the next notch as soon as the stud is removed from the slot in the Geneva wheel.

As shown in Figures 1, 4 and 9, a plurality of pins 57 project from each of the faces 49 of the turret 3. Decalcomania strips 58 are impaled on these pins 57 by the feeding mechanism 2, the pins being arranged to pierce the strips 58 between decalcomanias 58A (Figure 9).

The magazine 1 is shown in detail in Figures 6 and 7, and consists of angle iron vertical pieces arranged to form a pair of channels 59 and 60 for holding a large supply of the decalcomania strips 58. These strips are placed in the channels 59 and 60 with the decalcomanias 58A face down and are prevented from falling out of the bottom by a plate 61 which is arranged to slide away from the channels on a pair of horizontally disposed bars 62-62.

The feeding mechanism 3 (Figures 6 and 7), for transferring the strips of decalcomanias from the magazine 1 to the faces 49 of the turret, comprises a plate 63 secured to the end of a shaft 64 reciprocally and rotatably supported in bearings 65 and 66 (Figure 2) which are mounted on uprights 67 and 68, respectively. Reciprocation of shaft 64 causes the plate 63 to slide on bars 62. The plates 61 and 63 are substantially the same thickness, so the plate 63 can slide under the channels 59 and 60 and move the plate 61 away without disturbing the decalcomania strips 58. Movement of plate 61 away from channels 59 and 60 is resisted by a pair of springs 69-69 which surround pins 70-70 mounted on a brace 71 extending between the bars 62. The pins 70 have their ends disposed in apertures 72 formed in plate 61 so the plate will be guided as it slides to and from its position below the channels 59 and 60. When the plate 63 moves the plate 61 from under the channels 59 and 60, the decalcomania strips 58 in the bottom of the magazine are prevented from sliding out with plate 61 by a pair of pins 73 which are attached to a brace 74 (Figure 3) on channels 59 and 60 and extend into grooves 75-75 formed in the top surface of plate 61.

The mechanism for reciprocating the shaft 64 and plate 63 is actuated by a drum cam 76 on the main shaft 36 of the machine. This mechanism, as shown in Figures 2, 3 and 6, consists of a pair of levers 77 and 78 mounted on opposite ends of a rock shaft 79 that is journaled in a U-shaped bracket 80 which extends downwardly from horizontal member 26 and a similar member 81 connecting the sides of the framework. The lever 77 carries at its upper end, a roller 82 in position to engage the face of cam 76, and the lower end of lever 78 is formed with a toe 83 that is adapted to engage a collar 84 that is rigidly mounted on the shaft 64. A compression spring 85 is arranged on the shaft 64 between the bearing 66 and a collar 86 to normally force the shaft 64 toward the front of the machine. The forward limit of the shaft 64 is determined by a collar 87A (Figure 2) on the shaft which is arranged to engage the bearing 65 when the plate 63 is aligned with one of the faces 49 on the turret.

For each revolution of the main shaft 36, the drum cam 76 will move roller 82 and lever 77 causing the rock shaft 79 to oscillate and move the toe 83 of lever 78 against the collar 84. This will cause the shaft 64 to move toward the rear of the machine against the action of spring 85 and thereby move the plate 63 under the channels 59 and 60. At this point, as will herein-after be more fully described, suction is applied to holes 87 in the upper face of the plate 63 through hose connections 88-88 and passage 89, whereby the bottom decalcomania strip is held to the plate 63 while it is returned to its forward position by the action of spring 85. A pair of pins 90-90 are adjustably mounted on a brace 91 extending between the channels 59 and 60. These pins are adjusted so their lower ends are spaced from the surfaces of plates 61 and 63 a distance equal to the thickness of one strip of decalcomanias 58. Thus, as the plate 63 removes the bottom strip 58 from the magazine 1, the other strips are retained therein by the pins 90.

After the plate, with a strip 58 of decalcomanias held on its face by suction, has returned to its forward position, it is rotated counter-clockwise 90° to impale the strip 58 on the pins 57 projecting from the faces 49 of the turret. As shown in broken lines in Figure 7, the 90° rotation of the plate 63 brings it into engagement with the face 49 that is in position A so the pins 57 on the face 49 will slide in the holes 87 and thus pierce the decalcomania strip 58. After this occurs, suction is relieved from the plate 63 and it is returned to its horizontal position, leaving the strip 58 on the face of the turret.

The mechanism for rotating the shaft 64 is actuated by a cam 92 and is shown most clearly in Figure 8. This mechanism includes a lever 93 that is pivotally supported at one end by a stud 94 projecting from a bracket 94A mounted on horizontal member 26, and is pivotally connected at its other end to a link 95. The central portion of the lever 93 is formed with a follower 93A that is arranged to engage the cam 92. An arm 96 projects from the collar 86 on shaft 64 and is connected to the link 95, so movement of lever 93 by cam 92 causes the collar 86 and shaft 64 to oscillate. A counter weight 97 is attached to collar 86 to return the shaft 64 to its normal position as the cam 92 permits the lever 93 to return to its normal position. The pivotal connections at the ends of the link 95 have sufficient play so the rotating mechanism will not interfere with the reciprocation of the shaft 64.

As will readily be seen from the above description, each revolution of the main shaft 36 will effect one complete operation of the feeding mechanism. The drum cam 76 first causes plate 63 to reciprocate, under channels 59 and 60 to remove one decalcomania strip 58, by application of suction to the plate, and return with the strip to a position in alignment with the turret 3. The cam 92 then actuates mechanism which causes the shaft 64 and plate 63 to rotate 90° to impale the decalcomania strip on the pins 57 on the face 49 of the turret that is in position A. The counterweight then returns the shaft 64 and plate 63 to their original positions, and the feeding mechanism is ready for another cycle of operation.

After a strip of decalcomanias has been placed on the face of the turret in position A, the turret is indexed one-eighth of a revolution by the stud 42 and Geneva wheel 44. This moves each of the

faces of the turret one indexing step, so the face that was formerly in position A is moved to position B.

The decalcomania strip on the face of the turret that is in position B is partially immersed in the liquid in container 4. As the turret is further indexed, the decalcomania strip is moved to position C where it is entirely submerged, and then to position D where it is again only partially submerged. The time interval required to index the turret through these three positions permits the strip 58 to absorb sufficient moisture to dissolve the adhesive which holds the decalcomanias 58A on the strip. This loosening of the decalcomanias from the strip is completed during the time required for the strip to be indexed through positions E and F. When the strip reaches position G, the decalcomanias are ready to be removed by the transfer mechanism 5 which will now be described.

The transfer mechanism 5 consists of a slide 98, fitted on and reciprocally supported by a dovetail member 99 (Figure 11) which is mounted on horizontal members 53 and 81. The slide 98 is reciprocated by a drum cam 100 (Figures 4 and 11) mounted on the main shaft 36 and having a cam groove 101 formed in its surface that is adapted to engage a stud 102 attached to the under side of the slide 98 and extending through a slot 103 in the dovetail support 99. The groove 101 in the drum cam 100 is formed so the slide 98 will reciprocate forward and backward once for each revolution of the main shaft 36. As shown in Figures 9 and 10, the slide 98 carries a transversely extending base plate 104 which has a pair of vertically disposed plates 105-105 mounted on its end portions that support a pair of transversely extending rods 106-106. Four holders 107, 108, 109 and 110 for pick-ups 111, are slidably mounted on rods 106, and one centrally located holder 112 is affixed to the base plate 104.

All of the holders have angularly extending projections 113 which are drilled to hold two pick-ups 111 laterally offset with respect to each other. When the slide is in its retracted position as shown in Figures 1 and 9, the holders are held closely adjacent each other in nested relation on the central portions of the rods 106 so each of the pick-ups 111 is aligned longitudinally with one of the decalcomanias 58A on the strip 58. As the slide is moved forward by the drum cam 100, suction is applied to the pick-ups and they are moved downward toward the turret to remove the decalcomanias from the strip. The slide continues forward and the holders spread laterally as shown in Figure 10, to align the pick-ups 111 with the packages of cigarettes in the carton 6, at which time fluid pressure is applied to the pick-ups 111 which forces the decalcomanias onto the cigarette packages. The slide then returns to its retracted position and the holders move to their central positions. The mechanism for effecting the movements of the pick-ups 111 and their holders will now be described.

Each of the slideable holders has a pin 114 projecting upwardly from its body portion. The holders 107 and 108 are connected by a link 115 which fits snugly on the pin on the holder 107 and has a lost motion connection with the pin on holder 108. A similar link 116 fits on the pin on holder 110 and has a lost motion connection with the pin on holder 109. A tension spring 117, which is connected between the pins on holders 108 and 109, tends to draw these two holders toward one another. A pair of posts 118-118 are

mounted on the horizontal member 53 on opposite sides of the slide 98. Tubes 119-119 are pivotally connected to the upper end portions of the posts 118 and are arranged in telescoping relation with rods 120-120 which are pivotally attached to pins 114 on the holders 109 and 110. The rods 120 have pins 121-121 formed on their end portions that are adapted to slide in slots 122-122 to form a lost motion connection with the tubes 119. Compression springs 123-123 surround the rods 120 between the pins 114 and nuts 124 on the ends of the tubes 119 to tend to force the holders 107 and 110 toward the center of the rods 106 as shown in Figure 9.

During the first part of the forward motion of the slide 98, the pins 121 slide in slots 122 so the holders retain their central nested positions due to the force of spring 117 and springs 123. After the pick-ups 111 have passed over the turret 3 and removed the decalcomanias 58A from strip 58, the pins 121 reach the ends of slots 122 so during further forward movement of the slide, the holders 107 and 110 spread outwardly. After this occurs, the lost motion connections between the links 115 and 116 and the pins on holders 108 and 109 are taken up until finally these holders also spread outwardly. When the pick-ups reach a position over the cigarette packages in the carton 6, they are spread as shown in Figure 10 and fluid pressure is applied to the pick-ups so the decalcomanias are blown onto the packages. The slide then returns to its retracted position and the spring 117 with springs 123 return the holders to their central nested positions.

Each of the pick-ups consists of a body portion 125 from which projects a rod 126 that is slidably mounted in the projection 113 of the holder. A head 127 mounted on top of the rod 126 contains a ball 128 for engaging a cam bar 129 as the slide 98 moves the pick-ups over the turret. A compression spring 130 surrounds the rod 126 between the projection 113 and the head 127 to normally hold the pick-up in its uppermost position with the body portion 125 directly beneath the projection 113. As clearly shown in Figures 12 and 13, the body portion has a hollow shoe 131 attached to its lower end by a projection 132 extending upwardly from the shoe. A hose connection 133 is formed on the shoe 131 through which suction and pressure are applied to act on the decalcomanias through a number of small holes 134 formed in the bottom face of the shoe.

The cam bar 129 is supported directly over the turret by rods 135 which are mounted on posts 136 on the top of the framework. As the slide 98 moves forward, the pick-ups are moved downwardly toward the decalcomania strip on the turret by engagement of balls 128 with the cam bar 129. At the same time, suction is applied to the pick-ups which draws the decalcomanias away from the turret. The downward motion of the pick-ups is effected independently of and without interrupting their forward movement. This results in a sweeping action for lifting the decalcomanias from the turret. Although the bottom face of the shoe 131 may be brought into direct contact with the strip 58 to effect the removal of decalcomanias therefrom, it has been found that the decalcomanias may be readily removed with a small clearance between the strip and the shoe of the pick-up. By maintaining a small clearance between the decalcomanias and the pick-ups, the possibility of scarring or wrinkling the decalcomanias is greatly reduced.

After the decalcomanias have been transferred

from the strip 58 to the packages of cigarettes, the slide returns to its retracted position and the indexing mechanism moves the turret another step. The face 49 that was formerly in position G is moved to position H where the used strip is removed by the rake 7. As shown in Figures 1 and 14, the rake has a series of teeth 137-137 and is attached to a reciprocating rod 138 by means of a bar 139. Bearings 140 and 141 mounted on horizontal members 65 and 81, respectively, support the rod 138. A bar 142 is attached to the slide 98 and slides between the collars 143 and 144 which are secured to the rod 138, thereby reciprocating the rod and the rake. The rake is normally held in its rearmost position by a compression spring 145 which surrounds the rod 138 between the bearing 140 and the collar 143. A link 146 is attached to the rod 138 and is arranged to slide on a stud 147 projecting from bearing 140 to prevent rotation of the rod and thus hold the rake in position to move across faces 49 of the turret. The teeth of the rake are arranged to slide in grooves 148 formed between the pins 57 on each face of the turret. Each time the slide 98 reciprocates, it operates the rake to remove the used strip 58 from the face of the turret that is in position H. After the strip is removed, the turret is indexed and the face 49 is moved from position H to position A where it is ready to receive another strip of decalcomanias from the feeding mechanism 2.

As shown in Figures 1 and 3, the mechanism for applying suction to the feeding mechanism and suction and pressure to the pick-ups will now be described. The source of the suction and pressure is an air pump 150 having an inlet 151 and an outlet 152. The pump is driven by a belt 153 that is connected between a pulley 154 on the motor 24 and a pulley 155 on the pump. The application of suction and pressure to the feeding mechanism and the pick-ups of the transfer mechanism is controlled by seven valves 156, 157, 158, 159, 160, 161, and 162 which are actuated by cams 163, 164, 165, 166, 167, 168, and 169, respectively. The cams are mounted on a cam shaft 170 which is supported in bearings 171 and 172 and driven by a chain 173 that is connected between sprockets 174 and 175 on the main shaft 36 and the cam shaft 170, respectively. The sprockets 174 and 175 are identical so the cam shaft 170 will revolve once for each revolution of the main shaft 36.

A pair of posts 176 are supported on the horizontal member 17 to carry a rod 177 on which are pivotally mounted cam levers 178, one for each of the cams and valves. Each of these cam levers has a follower 179 on one end for engagement with its cam and is pivotally connected at the other end to its respective valve stem 180. The cams and lever mechanisms are identical for each of the valves with the exception of the shapes of the cams. The relative positions and shapes of the cams as well as the various connections of the fluid system are shown diagrammatically in Figure 15.

The positions of the cams are shown in this view as they appear after the slide 98 has started its forward movement, and just as the front pick-ups pass over the strip of decalcomanias on the turret. At this instant in the cycle of operation, suction is applied to the front pick-ups by the opening of valve 157 which places the inlet 151 of the pump, through conduits 181 and 182, in communication with hose connection 183 leading to a manifold 184 (Figure 3) which is connected to each of the front five pick-ups by tubes 185.

Valve 162 is also open at this point, to permit the pump to exhaust to the atmosphere. After the front pick-ups have removed decalcomanias from the strip, valve 156 is opened to admit suction to the back pick-ups through hose connection 186, manifold 187 (Figure 3) and tubes 188. When the slide 98 reaches its forwardmost position, it dwells for a short interval with the pick-ups arranged over the cigarette packages. At this time, valve 157 closes to shut off suction from all of the pick-ups, and valve 162 closes to cut off the outlet of the pump from the atmosphere. Next, valve 158 opens to open the inlet of the pump to the atmosphere, and valve 161 opens to apply fluid pressure to all of the pick-ups by connecting the outlet from the pump through conduit 189 with conduit 190 and hose connections 183 and 186. The pressure applied to the pick-ups blows the decalcomanias onto the packages of cigarettes. At the same time that pressure is applied to the pick-ups, valve 159 opens to apply suction to the plate 63 of the feeding mechanism. The opening of valve 159 places the inlet 151 of the pump, through conduits 181 and 191, in communication with hose connection 192 leading to manifold 193 which is connected to the plate 63 by flexible tubes 194 (Figures 1 and 2). When the valve 159 opens, the plate 63 has been moved under the channels 59 and 60 to remove a strip of decalcomanias. While suction is being applied to plate 63, valve 158 closes to cut off the inlet to the pump from the atmosphere and valve 162 opens to connect the outlet of the pump with the atmosphere. Suction is continuously applied to the plate 63 until it has moved forward and then rotated to impale the strip on the pins 57 on the turret, at which time the valve 159 closes. At the same time, the valves 156 and 161 close to cut off pressure from the pick-ups. Before the plate 63 is moved away from the turret, valve 160 opens to connect the inlet of the pump with the atmosphere and relieve the suction from the plate 63.

After all of the mechanisms of the machine have completed their operations, the turret is indexed to another position. As soon as the indexing step is completed, the machine is ready to begin another cycle by moving the slide 98 forward and opening valve 157.

The tubes 185 and 188 are flexible to permit movement of the pick-ups relative to the slide 98 without affecting the fluid connections. Likewise, the tubes 194 are also flexible to permit reciprocation and rotation of the plate 63. The degree of pressure and suction that is applied to the front and back pick-ups is adjusted by volume control valves 195 and 196, respectively. A similar valve 197 controls the suction applied to the feeding mechanism.

When the machine is used for the application of decalcomanias to eggs, a modified form of transfer mechanism such as that shown in Figures 16, 17 and 18 may be used. In the particular illustration of the invention, the decalcomanias are applied to a dozen eggs in a box holding them in two rows. When decalcomanias are applied to eggs, it is necessary to place the decalcomania almost exactly in the center of the egg. For this reason, it is necessary to have the front and back pick-ups aligned longitudinally as well as transversely in order to accurately place the decalcomanias on the eggs.

A slide 201 used in this modification is constructed and supported substantially the same as the slide 98 which has been previously described. The slide 201 carries four holders 202, 203, 204

and 205 slidably mounted by means of a dovetail joint 206 (Figure 17) on a base plate 207. A stationary holder 208 is rigidly attached to the base plate 207. A plurality of arms 209, 210, 211 and 212 are hinged to the reciprocable holders 202, 203, 204 and 205, respectively, and a pair of similar arms 213 and 214 are hinged to the stationary holder 208. Each of the arms carries a pair of pick-ups 215 and is adapted to pivot about one of these pick-ups by means of hinge joints 216. As shown in Figure 17, a bushing 217 for the rear pick-up forms a hinge pin for the hinge 216. Each of the pick-ups 215 is substantially the same as pick-ups 111 which have already been described, so a further description is unnecessary. The main difference is that a roller 218 is used in the pick-ups 215 in place of the ball 128.

The modified mechanism for spreading the holders from their nested positions and aligning the front and rear pick-ups after they have removed the decalcomanias from the turret consists of a pair of bell crank levers 219 and 220 pivotally supported on opposite sides of the slide 201 at 221 and 222, respectively. The lever 219 has one arm 223 pivotally connected to a link 224 having a slot 225 adapted to slide on a pin 226 which is mounted on the framework of the machine. Another arm 227 of the lever 219 is pivotally connected to a link 228 which is pivotally connected to a pin 229 on the holder 202. A link 230 is also pivotally connected to the pin 229 and has a slot 231 in which a pin 232 on the holder 203 is adapted to slide. As the slide 30 moves forward, the pin 226 slides in the slot 225 of link 224 so the bell crank lever 219 is not moved. After the pick-ups have passed over the strip 58 and removed the decalcomanias, pin 226 engages the end of slot 225 and moves the lever 40 219 so the arm 227 pulls links 228 and 230. This causes the holder 202 to move to the left, and after the lost motion connection of pin 232 and slot 231 is taken up, holder 203 is also moved to the left, the final position of these holders being shown in broken lines in Figure 16. In a similar manner, bell crank lever 220 on the opposite side of the slide acts through links 233 and 234 to move holders 204 and 205 to the spread position shown in broken lines in Figure 16. A tension spring 235 connected between the bell crank levers 219 and 220, and a tension spring 236 connected between the pin 232 on holder 203 and a similar pin 237 on holder 204 tend to pull the four movable holders to their central nested positions as shown in full lines. When the slide returns to its retracted position, the springs 235 and 236 return the holders to their original positions.

In order to bring the front and rear pick-ups into longitudinal alignment so they will be positioned directly over the eggs, the arms of the various holders are pivoted about the hinge joints 216. The mechanism for pivotally moving the arms consists of links 238 and 239 connected to pins 240 and 241 on the arms 209 and 212, respectively, and having lost motion slot connections 242 and 243 with a pin 244 on the stationary holder 208. As the holders 202 and 205 are spread during the forward movement of the slide 201, the links 238 and 239 cause the arms 209 and 212 to swing about hinge joints 216 until the pick-ups 215 carried by each of the arms are longitudinally aligned as shown in broken lines in Figure 16. The lost motion connections 242 and 243 permit the holders to move almost

to their final spread positions before swinging the arms.

A pair of links 245 and 246 are pivotally connected to a pin 247 on the arm 210, and have lost motion slot connections 248 and 249 with pins 250 and 251 on the arms 209 and 213, respectively. As the holders 202 and 203 move to their spread position, the lost motion connections 248 and 249 are taken up. Thus, when link 238 swings arm 209, links 245 and 246 are moved and cause arms 210 and 213 to swing to position the pick-ups in longitudinal alignment as shown in broken lines in Figure 16. Similarly, as the arm 212 swings, links 252 and 253, which are pivotally connected to a pin 254 on arm 211 and have lost motion slot connections 255 and 256 with pins 257 and 258 on the arms 212 and 214, respectively, cause the arms 211 and 214 to swing until the pick-ups 215 are longitudinally aligned as shown in broken lines in Figure 16. After the decalcomanias have been blown onto the eggs by the application of fluid pressure to the pick-ups, the slide is retracted and the arms and holders are returned to their nested positions. As shown in Figures 17 and 18, a link 259 is connected between each pair of pick-ups to keep the rollers 218 aligned.

Instead of submerging the strips of decalcomanias in liquid in a tank, the turret wheel may be modified to carry the liquid and automatically moisten the strips of decalcomanias as they are indexed from the feeding mechanism to the transfer mechanism. One modification of the turret wheel for this purpose is shown in Figures 19 and 20. In this modification, a hollow turret wheel 260 adapted to hold a quantity of liquid is mounted on a shaft 261 which corresponds to the shaft 45 of the previously described machine and is supported by a bearing 262 mounted on a horizontal member 263 of the framework. The front of the turret 260 has an opening 264 through which liquid may be added when necessary. The turret wheel has eight faces 265, each of which is provided with a series of small holes 266. Channel members 267 are attached to each of the faces 265 by bolts 268 and these channel members have holes 269 formed in their web portions that are arranged to correspond with the holes 266. The channel members 267 are packed with felt or similar absorbent material 270 which is held in place by thin strips 271 extending between the sides of the channel members. Small holes 272 are formed in the strip 271 so that liquid absorbed by the felt 270, through holes 266 and 269, is transferred to the strip of decalcomanias 58 to loosen the decalcomanias therefrom.

In some cases, difficulties have been caused by the tendency of the strips of decalcomanias 58 to stretch or expand as they become saturated. In this modified form of turret, provision is made to compensate for this change in size of the decalcomania strips. The strips of decalcomanias 58 are impaled on central pins 273 projecting from the channel 267 and pins 274 formed on arms 275 of bell crank levers which are pivotally mounted at opposite ends of each of the channels 267. The other arms 276 of the bell crank levers are connected to the sides of the channels 267 by tension springs 277 which tend to pull the pins 274 at the ends of the channels in opposite directions. A segment 278 of a wheel is mounted on the horizontal member 263, and has a rim 279, the inner side of which is adapted to engage rollers 280 that are mounted on the arms 276 of

the bell crank levers. The segment 278 is arranged to engage the rollers 280 on the faces of the turret that are in positions A and H to move the pins 274 on the opposite ends of the faces toward each other by moving the rollers 280 toward the center of the turret.

When strips of decalcomanias 58 are placed on the face of the turret in position A, the pins 274 are contracted. As the face of the turret is indexed to position B, the rollers 280 become disengaged from the rim 279 and springs 277 tend to move them in opposite directions so any expansion of the strip of decalcomanias is taken up by the movement of the pins 274. The face of the turret in position H has its rollers 280 in engagement with the rim 279 so the pins 274 are contracted to facilitate removal of the strip of decalcomanias by a rake, not shown, similar to the rake 7 in the machine previously described. The teeth of the rake used with this modified form of turret move through spaces 281 formed between the pins 274 and the ends of the channels 267, and grooves 282 on each side of the pins 273.

Although the embodiments of the invention disclosed herein illustrate the simultaneous application of ten and twelve decalcomanias, respectively, it is contemplated that any number of decalcomanias may be applied without departing from the scope of the invention. It is obvious that the invention may be used for any types of articles and is not restricted to machines for applying decalcomanias to cigarette packages and eggs.

What I claim is:

1. In a machine for applying decalcomanias having a support provided with impaling means for holding a strip of decalcomanias in fixed position thereon, a feeding mechanism comprising a magazine for a supply of strips of decalcomanias, a perforated plate for removing a single strip of decalcomanias from said magazine, said perforations cooperating with said impaling means to transfer said single strip of decalcomanias to a predetermined position on said support, and mechanism for intermittently moving said member between said magazine and said support.

2. In a machine for applying decalcomanias to articles, a movable support for holding the decalcomanias, means for moistening said decalcomanias, means for transferring the decalcomanias from said support to the articles, mechanism for indexing said support with respect to said moistening means and said transferring means, and mechanism for operating said transferring means once for each operation of said indexing mechanism.

3. In a machine for applying decalcomanias to articles, a turret having a plurality of faces adapted to carry strips of decalcomanias, means for moistening said strips, means for transferring said decalcomanias from said strips to the articles, and mechanism for indexing said turret to successively present each of said faces to said moistening means and said transferring means.

4. In a machine for applying decalcomanias to articles, a turret having a plurality of faces, means for placing strips of decalcomanias one at a time successively on each of said faces, means for moistening said strips, means for transferring said decalcomanias from said strips to the articles, and mechanism for indexing said turret to successively present said faces to each of said means.

5. In a machine for applying decalcomanias

to articles, a turret having a plurality of faces, means for placing strips of decalcomanias one at a time successively on each of said faces, means for moistening said strips, means for transferring said decalcomanias from said strips to the articles, means for removing said strips from said faces, and mechanism for indexing said turret to successively present said faces to each of said means, each of said means being operated once for each operation of said indexing mechanism.

6. In a machine for applying decalcomanias, a turret having a plurality of faces for carrying decalcomanias, means carried by said turret for moistening said decalcomanias, and mechanism for removing the moistened decalcomanias from said faces.

7. In a machine for applying decalcomanias, a turret having a plurality of faces, means for holding strips of decalcomanias on said faces, means for moistening said strips, mechanism for moving said holding means to compensate for change in size of said strips, and means for removing said decalcomanias from the strips on said turret.

8. In a machine for applying decalcomanias having a support for holding a plurality of decalcomanias arranged in a single row, means for transferring decalcomanias from the single row on said support to articles arranged in more than one row comprising a plurality of elements for transferring decalcomanias from said support to said articles, said elements being arranged in rows corresponding to the rows of articles and each element being aligned with one of the decalcomanias in said single row, mechanism for moving said elements transversely of said row of decalcomanias, and suction means actuated as each row of elements moves across said row of decalcomanias for applying suction to said elements to cause them to remove decalcomanias from said row.

9. In a machine for applying decalcomanias, a support for holding a plurality of decalcomanias in spaced relation, and means for transferring said decalcomanias from said support to articles, said means including a plurality of elements and mechanism for moving said elements laterally to apply said decalcomanias in different spaced relation on said articles.

10. In a machine for applying decalcomanias, a support for holding a plurality of decalcomanias, a plurality of elements for transferring said decalcomanias from said support to a plurality of articles, and mechanism for moving said elements in one direction from said support toward said articles and in a different direction to align with said articles.

11. In a machine for applying decalcomanias, a support for holding a plurality of decalcomanias arranged in spaced relation in a single row, and means for transferring said decalcomanias from said support to a plurality of articles arranged in differently spaced relation in more than one row, said means including a plurality of elements arranged in nested relation for removing the decalcomanias from said support and mechanism for spreading said elements to align them with said articles.

12. In a machine for applying decalcomanias, a support for holding a plurality of relatively closely spaced decalcomanias, and means for transferring said decalcomanias from said support to a plurality of relatively widely spaced articles, said means including a plurality of elements for removing the decalcomanias from said

support, means for moving said elements in one direction toward said articles and in another direction to align them with said articles, and means for aligning said elements longitudinally in pairs.

5 13. In a machine for applying decalcomanias, a support for holding a plurality of decalcomanias in a single row, a second support for holding a plurality of articles arranged in a double row, and means for transferring decalcomanias from said support to said articles, said means including a plurality of elements arranged in two rows, the elements in one row being laterally offset with respect to the elements in the other row, mechanism for moving said elements longitudinally from said support to said articles, and mechanism for moving the elements in the two rows into longitudinal alignment with each other over said articles.

10 14. In a machine for applying decalcomanias, a support for holding a decalcomania, an element for transferring said decalcomania from said support to an article, means for moving said element toward said article, and additional means for moving said element toward said support without interrupting the first mentioned movement of said element.

15 15. In a machine for applying decalcomanias, a support for holding a decalcomania, an element for transferring said decalcomania from said support to an article, means for moving said element toward said article, additional means for moving said element toward said support without interrupting the first mentioned movement of said element, and means for applying suction to said element during said movement toward said support to remove the decalcomania from said support.

20 16. In a machine for applying decalcomanias, a support for holding a plurality of decalcomanias, a plurality of elements for transferring said decalcomanias from the support to a plurality of articles, means for moving said elements in one direction toward said articles and in a different direction to align with said articles, additional means for moving said elements toward said support without interrupting their movement in said one direction, and means for applying suction and fluid pressure successively to said elements to remove the decalcomanias from said support and to apply them to said articles.

25 17. In a machine for applying decalcomanias to articles, a magazine for holding a plurality of sheets of decalcomanias, a turret having a plurality of faces, each of said faces having means for positively securing a sheet of decalcomanias thereon, mechanism for feeding sheets of decalcomanias one at a time from said receptacle to said means for securing them on the turret, and means for transferring decalcomanias from the sheets on said turret to the articles.

30 18. In a machine for applying decalcomanias, a magazine for holding a plurality of sheets of decalcomanias, a turret having a plurality of faces, feeding mechanism for removing sheets of decalcomanias from said magazine and impaling said sheets on pins projecting from the faces of the turret, means for transferring decalcomanias from the sheets on said turret to articles, and mechanism for indexing said turret with respect to said feeding mechanism and said transferring means.

35 19. In a machine for applying decalcomanias having a support provided with retaining means

for holding a strip of decalcomanias in fixed position thereon, a feeding mechanism comprising a magazine for a supply of strips of decalcomanias, a member for removing a single strip of decalcomanias from said magazine and co-operating with said retaining means to transfer said single strip of decalcomanias to a predetermined position on said support, and mechanism for intermittently moving said member between said magazine and said support.

20. In a machine for applying decalcomanias, a turret adapted to carry decalcomanias, means for moistening said decalcomanias, means for

transferring said decalcomanias from said turret to an article, and mechanism for indexing said turret to successively present said decalcomanias to each of said means.

- 5 21. In a machine for applying decalcomanias, a turret adapted to carry decalcomanias, means for placing decalcomanias on said turret, means for moistening said decalcomanias, means for transferring said decalcomanias from said turret to an article, and mechanism for indexing said turret to successively present said decalcomanias to each of said means.

WILLIAM M. MUIR.
